PACKET OF CIGARETTES

William H. Saul, Brooklyn, N. Y.

Application February 12, 1936, Serial No. 63,632

1 Claim. (Cl. 312—31.2)

This invention relates to packets of cigarettes. It is particularly directed to a dated cigarette packet provided with a moistener or humidifier and the like articles, and intended to be discarded after being used once.

An object of this invention is to provide a packet of cigarettes marked with the date of packing, and having incorporated therewith means for keeping the cigarettes fresh, the construction being such that the packet may be discarded after the cigarettes have been used up, and the date being marked on the package in such manner as to safeguard against altering or changing the date after distribution of the packet from the factory.

In marketing a dated packet of cigarettes containing a moistener, it may be desirable to send back to the factory the packets unsold within a certain period from the marked date for the purpose of replacing the moistener with a new and fresh moistener, whereby the cigarettes may be kept fresh for an additional period. It is therefore a further object of this invention to provide a packet of the character described, so constructed that the moistener may be removed and replaced, the compartment containing the moistener preferably being sealed with a sticker or label bearing the date either of packing the cigarettes or of replacement of the moistener.

A still further object of this invention is to provide an economical, simple, compact and practical cigarette packet of the character described and for the purpose aforesaid.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claim.

In the accompanying drawing, in which is shown one of the various possible illustrative embodiments of this invention,

Fig. 1 is an elevational, cross-sectional view of a packet of cigarettes embodying the invention;

Fig. 2 is a cross-sectional view taken on line 2—2 of Fig. 1;

Fig. 3 is a cross-sectional view taken on line 3—3 of Fig. 1;

Fig. 4 is a cross-sectional view taken on line 4—4 of Fig. 1;

Fig. 5 is a view similar to Fig. 1, but illustrating a modified construction;

Fig. 6 is a partial, side elevational view of a packet shown in Fig. 5;

Fig. 7 is a cross-sectional view taken on line 7—7 of Fig. 5;

Fig. 8 is an elevational, cross-sectional view of the lower portion of the packet embodying another form of the invention;

Fig. 9 is a cross-sectional view taken on line 9—9 of Fig. 8;

Fig. 10 is an elevational, transverse cross-sectional view of a cigarette packet illustrating a still further modified construction; and

Fig. 11 is a perspective view of the moistener.

Referring now in detail to the drawing, 10 designates a cigarette packet embodying the invention. The same comprises a wrapper 11 of paper or other tearable material, having flaps folded at the bottom to form a bottom wall 12 and being open at the top. Within the wrapper 11 and resting on the bottom wall 12 thereof is a tubular member 13 made of paper or cardboard and having a bottom wall 14, a top wall 15 and side wall 16, and preferably being open at the ends. The member 13 substantially fits within the wrapper 11, and the top wall 15 thereof is formed with a plurality of perforations 18. Within the member 13 is a moistener or humidifier 20 for the cigarettes. The member 20 may be in the form of a prismatic slab of concentrated rum crystals, a piece or slab of apple, a strip of absorbent paper or fibrous material saturated with some humidifying liquid, or any other suitable material or substance.

Within the wrapper 11 and resting on the top wall 15 of the member 13 is an inner package 21 of wrapped cigarettes. The same may comprise an inner completely enclosing casing or wrapper 23 containing the cigarettes 24. The wrapper 23 may consist of flat sheets of superimposed paper and tin foil folded about the cigarettes and closed at the top and bottom. When the wrapped cigarettes are inserted within the wrapper 11, the top of the inner package is preferable substantially at the level of the upper edge 26 of the wrapper 11. The usual United States revenue stamp 27 may be pasted over the top wall of the inner package 21 and over the upper sides of the wrapper 11. The entire package may then be wrapped in a covering or enclosure 28 of Cellophane or other transparent sheet material.

The packet may be marked with the date of packing so that the retail purchaser, buying a package of cigarettes, may know the date of packing, and may therefore know whether he is 55

getting a fresh package of cigarettes. The dating may be made on any part of the package, either on the wrapper 11 or on the Cellophane wrapper 28. The date may be marked on a sticker or label pasted to the packet inside of the outer Cellophane wrapper so that the same is not accessible without destroying the outer Cellophane wrapper.

The date may furthermore be marked on a strip of paper 30 pasted to the top of the inner package 21, and as shown on the drawing, the revenue stamp 27 may be pasted over the said strip of paper, the dating appearing on a portion of said paper extending beyond said stamp so that the date may be read through the transparent outer wrapper. Since tampering with the revenue stamp is forbidden by law, the purchaser will be further safeguarded against tampering with the date on the packet. The bottom wall 34 of the inner wrapper 23 is preferably perforated as at 35 to establish communication between the compartment in which the cigarettes are contained and the moistener or humidifier 26.

The purchaser of a packet of cigarettes 10 may use the packet in the manner of the usual packet of cigarettes, by tearing open the top for withdrawing the cigarettes from the top. After the cigarettes are used up, the packet may be thrown away or discarded. It will now be understood that the casing or wrapper must be torn or partially destroyed to remove the cigarettes and hence there can be no refilling or reuse. If desired, the paper and tin foil inner wrapper may be omitted, and the cigarettes placed within the wrapper 11 on the tubular member 13 and being kept fresh by the moistener or humidifier 26, and in such event, the outer wrapper 11 is preferably provided with folded upper end portions forming a top wall, whereby the cigarettes, as well as the member 13, are completely enclosed by said last mentioned wrapper.

It may be desirable to market the packets of cigarettes in such a way that if a packet is not sold within a certain period from the date with which it is marked, the packet may be returned to the manufacturer and refurnished with a new moistener, for keeping the cigarettes moist and fresh for an additional period, and the packets then redated with the date when the fresh moistener was placed into the packet. A packet of cigarettes intended to be marketed in such manner is disclosed in Figs. 5 to 7. The packet 10a shown in said figures comprises a box, wrapper or casing 40 made of paper, cardboard or any other suitable tearable material. The box 40 has side walls 41. One of the side walls may have a flap 42 cut from the material thereof and provided with a tab extension 43, foldable on creased line 44. Within the box 40 and resting on the bottom wall thereof, is a partition member 45 having a top wall 46 and downwardly extending side walls 47, the bottom edges whereof contact the bottom wall of the box 40. Said top wall 46 may be formed with perforations 48. The cigarettes 24 may be placed in the compartment above the partition 46. The tab 43 may be inserted beneath the top wall 46 as shown in Fig. 5 of the drawing. Within the compartment 49, beneath the partition member 45 is a moistener 20. A seal 51 of any suitable shape may be pasted over the side wall 41 of the box to cover the opening in said side wall formed by folding the tab 43 inwardly beneath the top wall of the partition. The seal 51 may have the date of packing marked, printed or stamped thereon. If the packet is not

sold within a certain period from the date of packing, the same may be returned to the factory, the seal 51 removed, the flap 42 opened, and the moistener 20 replaced by a fresh moistener. The flap 42 may then be returned to its original position, and a new seal 51 placed on the box bearing the date when the moistener was replaced.

In Fig. 8, there is shown a packet 10b of cigarettes intended to be marketed in the same way as packets 10a. Said packet 10b comprises a box 10 or casing 55, likewise of paper or other tearable material, and having side walls 56. One of the side walls is formed with an opening 57 at the bottom end thereof. Within the box and resting on the bottom wall thereof is a partition 60 similar to the partition 45. Within the compartment 61, formed by the partition 60, is a small drawer 63 in which the moistener or humidifier 20 is placed. A seal 68 pasted on the outer surface of the box serves to close the openings 57. The date of packing may be marked or printed on the seal 68. If the packet is not sold and is returned to the factory, the seal may be removed, the drawer 63 withdrawn through the opening 57, and a new moistener placed therein. The drawer may then be again placed into the compartment 61 and a new seal bearing the date of replacement of the moistener may then be pasted or otherwise attached to the box to cover said opening 57.

In Fig. 10, there is shown another form of cigarette packet. The packet 10c of Fig. 10 comprises a tubular member 70 of oblong transverse cross-section. Within the tubular member 70 is a holder 71 having a bottom wall 72, a rear wall 73 and a front wall 74. The front wall 74 terminates short of the top of the tubular member 70. Extending from the upper end of the rear wall 73 is a top wall 76 provided with a downwardly extending flap 77 contacting the front surface of the upper end of the front wall 74. Within the member 71 and resting on the bottom wall 72 thereof is a perforated partition 80 similar to the partition 45. Within the compartment 81 formed by said partition is the moistener 20. The cigarettes 24 rest on the top of the partition. The revenue stamp 85 may be pasted over the top of the member 71 and over the top edges of the tubular member 70 so that said stamp must be destroyed to open the flap 77 for removing the cigarettes. A sticker or label or strip of paper 90 bearing the date of packing may be pasted to the box with part thereof disposed beneath the revenue stamp, and the dated part thereof exposed. The entire package may be covered by an outer wrapper 91 of Cellophane or other transparent material. The date on the label 90 may be seen through the transparent wrapper. The purchaser may remove the cigarettes 24 by first removing the Cellophane wrapper, then breaking open the top of the packet 10c, and pushing the holder 71 upwardly from the bottom. Placing of the label 90 beneath the revenue stamp is an additional safeguard to prevent altering or replacement of the dated label, since the same cannot be removed without destroying the revenue stamp.

It will thus be seen that there is provided a device in which the several objects of this invention are achieved, and which is well adapted to meet the conditions of practical use.

As various possible embodiments might be made of the above invention, and as various changes might be made in the embodiments set forth, it is to be understood that all matter herein set forth or shown in the accompanying drawing, is

to be interpreted as illustrative and not in a limiting sense.

Having thus described my invention, I claim as new and desire to secure by Letters Patent:

- 5   A cigarette packet comprising a casing of tearable material and having a bottom wall and side walls, a member within the casing having a perforated wall disposed parallel to the bottom wall of the casing, a pair of downwardly extending walls at the side edges of said perforated wall and having lower edges engaging the bottom wall of said casing, a humidifying member disposed
- 10

between said perforated wall and the bottom wall of said casing, a portion of said casing adjacent one end of said humidifying member being cut to form a tab, a dated paper seal pasted to said tab and casing to retain the humidifying member within said casing, and a plurality of cigarettes mounted on said perforated wall with the lower ends of the cigarettes adjacent said perforated wall, one end of said tab being bent into said packet beneath said perforated wall.
